UNITED STATES PATENT OFFICE.

LESLIE G. SHARP, OF CHICAGO, ILLINOIS.

ROOFING-SHINGLE.

SPECIFICATION forming part of Letters Patent No. 787,475, dated April 18, 1905.

Application filed June 18, 1904. Serial No. 213,060.

To all whom it may concern:

Be it known that I, LESLIE G. SHARP, a citizen of the United States, residing at Chicago, in the county of Cook and State of Illinois, 5 have invented a new and useful Improvement in Roofing-Shingles, of which the following is a specification.

My invention relates more particularly to improvements in roofing-shingles or shingle-tile made of plastic shale or clay and suitably burned in a kiln, although cement or any other plastic material that may be found well enough adapted to the purpose may be used in their manufacture and without undergoing 10 the aforesaid burning process.

My invention does not apply to what are commonly known as "interlocking" roofing-tiles of the kind that overlap each other but slightly at their ends and with a gutter or 15 groove along one side and an overhanging flange or a combined flange and tongue along the other side for connecting the tile side by side in forming a roof and to prevent leakage at the side joints; but my roofing-shingles or 20 shingles-tile are intended to form a roof by long overlaps and the mismatching or breaking of the joints on a somewhat similar plan to that of the old and well-known wooden shingles, excepting that my shingle-tile have 25 certain modifications and many novel and useful features that are not found in the aforesaid wooden shingles.

The object of my invention is to produce both plain and ornamental roofing-shingles or 30 shingle-tile that will be cheap to manufacture, light, strong, durable, and well adapted to make a fine-appearing, good, reliable, fire-proof, and waterproof roof for buildings.

Heretofore shingle-tile like the ordinary 35 wooden shingles have been made of oblong rectangular form of uniform width from one end to the other, and as the water that gets into the side joints usually spreads but little between the upper and lower tiles until it 40 runs out at the lower end it will be seen that by the adoption of suitable means for confining the water so it cannot get far away from the joint until it runs out under the lower end of the tile considerable material in the 45 upper part of the tile could be cut out or

dispensed with, thereby rendering the roof considerably lighter than if made of shingle-tile of the old form. Another very important advantage is gained by cutting away the unnecessary material, because it so greatly 55 reduces the surface area of the tile that it becomes practicable to manufacture or burn the tile without the excessive warpage and resultant loss therefrom that usually occurs in tile of larger surface areas. It will be seen 60 that I have also embodied a series of flanges and ribs in my shingle-tile that will be very effective in keeping out wind-driven snows and rains. The foregoing with other important features are hereinafter more fully described and claimed. 65

In the accompanying drawings, illustrating my invention, similar letters and numerals refer to similar parts throughout the several views. 70

Figure 1 is a front elevation of a number of my shingle-tile assembled as part of a roof, showing one of the tile in broken section. This view shows one of the tile at the right or gable end as of modified form, such as is 75 also shown in Figs. 7 and 8. Fig. 2 is a longitudinal sectional view cut on line 2 2 of Fig. 1. Fig. 3 is a side elevation of one of my shingle-tile of the pattern of most of the tile shown in Fig. 1. Fig. 4 is a cross-sectional 80 view of parts of several tile assembled and as cut on line 4 4 of Fig. 2. Fig. 5 is a plan view of the face side of one of my shingle-tile, also shown in Figs. 2 and 3. Fig. 6 is a plan view of the bottom or under side of my 85 shingle-tile that is shown in Fig. 5. Fig. 7 is a plan view of the face side of a modified form of my shingle-tile sometimes used as a finishing-tile at the gable ends of roofs. Fig. 8 is a plan view of the bottom or under side 90 of the tile shown in Fig. 7. Fig. 9 is a plan view of the face side of one of my tile slightly modified. Fig. 10 is a plan view of the bottom or under side of the tile shown in Fig. 9. Fig. 11 is a perspective view of the face side 95 of one of my tile without the central raised part on the lower end of the face thereof that is shown in Fig. 9. Fig. 12 is a perspective view of the under side of my tile that is shown in Fig. 11. Fig. 13 is a perspective view of 100

the face side of one of my tile slightly modified from that shown in Fig. 11. Fig. 14 is a perspective view of the face side of one of my tile slightly modified from that shown in Fig. 11. Fig. 15 is a plan view of the face side of one of my tile with a part of the side flanges removed and showing a central raised part of slightly-modified form from those in some of the preceding views. Fig. 16 is a front elevation of a number of tile assembled as a part of a roof, these tile being of the pattern shown in Fig. 15. Fig. 17 is a plan view of the under side of a slightly-modified form of several of my tile assembled as in forming a roof on purlins and as laid on open or skeleton construction without using sheathing-boards as a roof foundation. This view shows my method of securing together the tile at points between the purlin-supports to dispense with some of the purlins that would otherwise be required. Fig. 18 is a longitudinal sectional view of my tile assembled and as cut on line 18 18 of Fig. 17. Fig. 19 is a cross-sectional view of parts of three of my tile assembled and as cut on line 19 19 of Fig. 17, this view, Fig. 19, being to more clearly show the method of securing my shingle-tile together by means of the downwardly-projecting lugs with holes made through them to receive the cross-pin, which cross-pin together with the aforesaid lugs are shown in whole form in this view.

My shingle-tile A is preferably made with its lower portion having parallel sides and of a rectangular form and its upper portion made narrower or neck-shaped, as shown in most of the figures of the accompanying drawings; but in some cases I depart from this rectangular outline by making the lower end or butt of the tile of a semicircular form, (not shown,) or I may modify the plan outline of the butt-end by adopting any other common and well-known shape therefor, and I may change the pattern or design of the centrally-located raised part on the butt-end of the tile into any other known pattern or design that may be found desirable for either ornamental or other purposes.

My shingle-tile A, as shown in Figs. 1, 5, and 6, are preferably made with an upwardly-projecting flange a , made on the face side thereof and extended along one side up to and across the upper end and down along the other side of the body part of the tile, and in some cases I make upwardly-projecting auxiliary flanges or ribs a' on the face of the tile joined to the aforesaid upwardly-projecting flange a . Nail-holes a^2 may be made down through the enlargements of the upwardly-projecting flange a for nailing the tile to the roof foundation B. These nail-openings being made above the face level of the tile water cannot get into them when the tile are laid one above another, as in roof construction. If desired, longitudinal gutters or grooves t may be made on the top of the upwardly-pro-

jecting flanges a , as shown in Fig. 9, for intercepting and leading to the lower part of the tile any water that may by capillary attraction or otherwise happen to get upon the top of said upwardly-projecting flange a .

On the butt-end of my tile I usually make a central raised part a^3 , which may be hollowed out from the under side of the body part, as shown in Fig. 6, and in some cases may have a downwardly-projecting flange z , made on the margin of the cavity of the hollowed-out portion of said central raised part, and extended across the upper part of said cavity or hollowed-out part I usually make a guard-rib a^4 for stiffening purposes and to also intercept any water or snow that may happen to get past the transverse-closing part a^5 , which is also extended across the said hollowed-out portion; but said transverse-closing part a^5 is preferably set back under a short distance from the lower end of the central raised part a^3 , which construction, as shown in Figs. 2 and 6, forms a recess or hood at the lower end of said central raised part. When water runs down the face of the tile, some of it is likely to follow along the lower end of the tile over to the upwardly-projecting flanges a or the side joints of the tile below, leaving the upper tile at that point; but the aforesaid recessed or hooded part serves to cause the water to leave the butt-end of the tile before it can get over as far as the side joints of the tile below, and aside from this important feature of protecting the joints the recessed or hooded end of the central raised part greatly improves its appearance as compared with making said transverse closing part clear out to or flush with the end of the said central raised part. When unbroken upwardly-projecting side flanges a are made on the lower part of the face side of the body part, I make what I herein term a "flange-opening" a^6 in the said transverse closing part a^5 to receive said side flanges a of the tiles that are laid below in forming a roof, and a similar flange-opening a^7 may also be made in the guard-rib a^4 , as shown in Fig. 6.

On the under side of the lower portion of the body part of my tile I make downwardly-projecting flanges a^8 at the sides and downwardly-projecting flanges a^9 at the lower end thereof, as shown in Figs. 3 and 6, and in some cases I make on the under side of the tile a downwardly-projecting joint-closing rib x , which when the tile are assembled overlaps on its inner side the transverse portion a^{10} of the upwardly-projecting flange a , so as to close that joint against any snow or water that may happen to blow up under the upper tile, and I sometimes make a short transverse upwardly-projecting joint-closing rib w on the face of the tile joined to the upwardly-projecting flange a , as shown in Fig. 5, and I may also make upwardly-projecting joint-closing parts v and v' on the top of the up-

- wardly-projecting flange α , as shown in Fig. 5, to overlap behind and more effectively close the joints of the top of the flange-openings α^6 and α^7 when the tile are assembled.
- 5 On the under side of the upper portion of the body part of my shingle-tile I usually make a downwardly-projecting longitudinally-disposed tapering flange or rib α^{11} for closing the opening that would otherwise be left between the bottom of the tile and the top of the sheathing-boards of the roof. This flange or rib α^{11} also serves to greatly strengthen and stiffen that portion of the tile, and the downwardly-projecting auxiliary flanges or ribs α' , made on the face of the tile, answer to continue such strengthening and stiffening farther down on the tile. To make a better finish at the gable ends of the roof, I may use a tile A', made of oblong rectangular outline with an upwardly-projecting flange α^{12} , made on the face and extending along one side up to and across the upper end and down along the other side of said body part and auxiliary flanges or ribs α' , as shown
- 10 in Figs. 1, 7, and 8, and with downwardly-projecting flanges α^{14} made on the sides and downwardly-projecting flanges α^9 along its lower end. On the upper portion of the under side of the body part I make downwardly-projecting longitudinally-disposed flanges or ribs α^{11} for strengthening and stiffening purposes and for closing the opening beneath the tile when laid on sheathing-boards, and a notch or opening α^{15} is made in the downwardly-projecting longitudinally-disposed flange or rib to receive the upwardly-projecting flange made on the face side of the upper end of a similar shingle-tile when the latter is laid beneath the first-mentioned shingle-tile in forming a roof. As constructed the aforesaid tile can be used for starting along one gable end of the roof, as well as for finishing along the other gable end, answering as either a right or a left gable tile. The downwardly-projecting ribs or flanges α^{11} close the opening beneath the tile, and therefore make a better finish at the gable ends than to use a tile A, although a different modification of the latter form (not shown) could be used at the gable ends. To break or mismatch the joints, a half-tile A² is used in every alternate course of tile and a whole under-eave tile A³ and a half under-eave tile A⁴ are used under the first course of tile at the eave, as shown in Figs. 1 and 2, as commonly used in forming shingle-tile roofs. In some cases to give the tile the proper slant a wooden strip C is used beneath the aforesaid under-eave tile. In some instances I make openings α^{16} in the upwardly-projecting side flanges α , as shown in Figs. 9, 11, and 12, to receive the downwardly-projecting flange α^9 , made on under side of the lower end of the tile, to enable them to fit together properly in assembling the tile to form a roof. When the openings
- 15 α^{16} are provided, it is not necessary to make a flange-opening in the lower end of the tile, as shown in some of the other views. To produce a plain-faced tile, I leave off the lower portion of the upwardly-projecting side flanges, 70 as shown in Fig. 13; but when said upwardly-projecting side flanges are left on, as shown in Fig. 14, a flange-opening α^{17} is made in the lower end of the tile. If it is desired to have a central raised part α^3 , but no upwardly-projecting side ribs, on the weather-exposed part of the tile, the lower portion of said side ribs may be left off, as shown in Figs. 15 and 16.
- 20 When it is desired to lay my shingle-tile on purlin-strips D, of wood, iron, or steel, 80 in open or skeleton construction and without the use of sheathing-boards as a roof foundation, I make a downwardly-projecting part α^{18} on the under side of the upper end of my tile, as shown in Figs. 17 and 18, said part α^{18} 85 being made for the purpose of hooking over a purlin D, and on the bottom of the tile I make a downwardly-projecting part α^{19} , with a hole α^{20} made through it to receive a wire 20, which may in any suitable manner be attached to a purlin D for securely holding the tile down in place, as shown. When it is desired to cheapen the construction by dispensing with one purlin at every alternate course of tile, I secure the tile together between the 90 purlins by means of downwardly-projecting lugs α^{21} , made on the under side of the tile, with holes α^{22} made through said lugs α^{21} to receive a cross-pin e, as shown in Figs. 17, 18, and 19. In some cases I may make a longitudinally-disposed joint-closing rib y on the under side close to the side of the neck part, as shown in Fig. 17, and may also join to said rib y a downwardly-projecting transverse joint-closing rib y', which is also shown in 95 Fig. 17, these overlapping joint-closing ribs y and y' being intended as additional safeguards against wind-driven fine snows, extra precautions being sometimes necessary where no sheathing-boards are used and when there is some suction between the inside and outside of the building.
- 100 In the ordinary wooden shingles there are no upwardly-projecting flanges, and as commonly made shingle-tile are not provided with upwardly-projecting flanges made along the sides and across the upper end of the tile and with downwardly-projecting flanges made along the sides and lower end of the under side of the tile and with a notch or opening 105 α^{15} , as my shingle-tile are made, the object in this system of upwardly and downwardly projecting flanges being to so confine the water as to prevent its getting into the upper side joints or getting up over the upper end 110 of the tile, thus making a safer and better roof than could be produced with wooden shingles or shingle-tile that are not provided with these important and efficient safeguards against wind-driven snows and rains.
- 115 120 125 130

While I have shown preferred forms of my invention, I do not wish to be limited thereto, as many slight modifications could be made therein without departing from the spirit of 5 my invention.

What I claim as my invention, and wish to secure by Letters Patent, is—

1. An improved shingle-tile, having a body part made of an oblong outline, a central raised part made on the lower portion of the face of said body part, said central raised part hollowed out from the under side of said body part, a downwardly-projecting flange z made on the under side of said body part on the 10 margin of the hollowed-out or cavity portion of said central raised part, and suitable means for securing said shingle-tile to a roof foundation, all when made substantially as and for the purposes set forth.
2. An improved shingle-tile, having a body part made of an oblong outline, a central raised part made on the lower portion of the face of said body part, said central raised part hollowed out from the under side of said body 15 part, a downwardly-projecting flange z made on the under side of said body part on the margin of the hollowed-out or cavity portion of said central raised part, and suitable means for securing said shingle-tile to a roof foundation, all when made substantially as and for the purposes set forth.
3. An improved shingle-tile, having a body part made of an oblong outline, a central raised part made on the lower portion of the face of said body part, said central raised part hollowed out from the under side of said body part and made with a transverse closing part 20 set back under, so as to form a recess or hood at the lower end of said central raised part, and suitable means for securing said shingle-tile to a roof foundation, all when made substantially as and for the purposes set forth.
4. An improved shingle-tile, having a body part made of an oblong outline, a central raised part made on the lower portion of the face of said body part, said central raised part hollowed out from the under side of said body 25 part and made with a transverse closing part set back under, so as to form a recess or hood at the lower end of said central raised part, a downwardly-projecting rib made across the upper part of the hollowed-out portion of said central raised part, and suitable means for securing said shingle-tile to a roof foundation, all when made substantially as and for the purposes set forth.
5. An improved shingle-tile, having a body 30 part made of an oblong outline, a central raised part made on the lower portion of the face of said body part, said central raised part hollowed out from the under side of said body part and made with a transverse closing part set back under, so as to form a recess or hood at the lower end of said central raised part, a downwardly-projecting flange made on the under side of said body part on the margin of the hollowed-out or cavity portion of said central raised part, and suitable means for securing said shingle-tile to a roof foundation, all when made substantially as and for the purposes set forth.

at the lower end of said central raised part, a downwardly-projecting flange z made on the under side of said body part on the margin of the hollowed-out or cavity portion of said central raised part, and suitable means for securing said shingle-tile to a roof foundation, all when made substantially as and for the purposes set forth. 70

6. An improved shingle-tile, having a body part made of an oblong outline, upwardly-projecting flanges made on the face portion of said body part and extended along its sides to the upper end of said body part, a downwardly-projecting flange made on the under side of said body part on its sides and lower end, a flange-opening made in said downwardly-projecting lower end flange, and suitable means for securing said shingle-tile to a roof foundation, all when made substantially as and for the purposes set forth. 75

7. An improved shingle-tile, having a body part made of oblong outline, a downwardly-projecting flange made on the under side of said body part on its sides and lower end, upwardly-projecting flanges made on the face portion of said body part and extended along its sides to the upper end of said body part, said upwardly-projecting flanges suitably notched or cut away to receive the aforesaid downwardly-projecting flange on the lower end of a similar tile when the latter is laid above the first-mentioned tile in forming a roof, and suitable means for securing said tile to a roof foundation, all when made substantially as and for the purposes set forth. 80 90

8. An improved shingle-tile, having a body part made of an oblong outline, upwardly-projecting flanges made on the face portion of said body part and extended along the sides to the upper end of said body part, a downwardly-projecting flange made on the under side of said body part along its sides and lower end, a central raised part made on the lower portion of the face of said body part, said central raised part hollowed out from the under side of said body part and made with a downwardly-projecting transverse closing part set back under, so as to form a recess or hood at the lower end of said central raised part, said upwardly-projecting flanges suitably notched or cut away to receive the aforesaid downwardly-projecting transverse closing part of a similar tile when the latter is laid above the first-mentioned tile in forming a roof, and suitable means for securing said tile to a roof foundation, all when made substantially as and for the purposes set forth. 100 110 115

9. An improved shingle-tile, having a body part made of an oblong outline, upwardly-projecting flanges made on the face portion of said body part and extended along the sides to the upper end of said body part, a downwardly-projecting flange made on the under side of said body part along its sides and lower end, a central raised part made on the lower portion of the face of said body part, said central raised part hollowed out from the under side of said body part and made with a transverse closing part set back under, so as to form a recess or hood at the lower end of said central raised part, a downwardly-projecting flange made on the under side of said body part on the margin of the hollowed-out or cavity portion of said central raised part, and suitable means for securing said shingle-tile to a roof foundation, all when made substantially as and for the purposes set forth. 125 130

portion of the face of said body part, said central raised part hollowed out from the under side of said body part and made with a transverse closing part set back under, so as 5 to form a recess or hood at the lower end of said central raised part, a flange - opening made in said transverse closing part, and suitable means for securing said shingle-tile to a roof foundation, all when made substantially 10 as and for the purposes set forth.

10. An improved shingle-tile, having a body part made of an oblong outline, a downwardly-projecting flange made on the under side of said body part on its sides and lower end, an 15 upwardly-projecting flange made on the face portion of said body part and extended along one side up to and across the upper end and down and down along the other side of said body part, said upwardly-projecting flange suitably 20 notched or cut away to receive the aforesaid downwardly-projecting flange on the lower end of a similar tile when the latter is laid above the first-mentioned tile in forming a roof, a notch or opening made in said down- 25 wardly-projecting flange adapted to receive the upwardly-projecting marginal flange on the upper end of a similar shingle-tile when the latter is laid beneath the first-mentioned tile in forming a roof, and suitable means for 30 securing said tile to a roof foundation, all when made substantially as and for the purposes set forth.

11. An improved shingle-tile, having a body part made of an oblong outline, an upwardly-projecting flange made on the face portion of said body part and extended along one side up to and across the upper end and down along the other side of said body part, a downwardly-projecting flange made on the under 40 side and lower end of said body part, a flange-opening made in said downwardly-projecting lower end flange, a notch or opening made in said downwardly-projecting side flange adapted to receive the upwardly-projecting marginal flange on the upper end of a similar shingle-tile when the latter is laid beneath the first-mentioned tile in forming a roof, and suitable means for securing said shingle-tile to a roof foundation, all when made substantially 45 as and for the purposes set forth.

12. An improved shingle-tile, having a body part made of an oblong outline, an upwardly-projecting flange made on the face portion of said body part and extended along one side 55 up to and across the upper end and down along the other side of said body part, a downwardly-projecting flange made on the under side along the sides and lower end of said body part, a central raised part made on the face of 60 the lower portion of said body part, said central raised part hollowed out from the under side of said body part, said upwardly-projecting flange suitably notched or cut away to receive the aforesaid downwardly-projecting 65 lower end flange of a similar shingle-tile when

the latter is laid above the first-mentioned tile in forming a roof, a notch or opening made in said downwardly-projecting flange adapted to receive the upwardly-projecting marginal flange on the upper end of a similar shingle- 70 tile when the latter is laid beneath the first-mentioned tile in forming a roof, and suitable means for securing said tile to a roof foundation, all when made substantially as and for the purposes set forth. 75

13. An improved shingle-tile, having a body part made of an oblong outline, an upwardly-projecting flange made on the face portion of said body part and extended along one side up to and across the upper end and down along the other side of said body part, a downwardly-projecting flange made on the under side and lower end of said body part, a central raised part made on the face of the lower portion of said body part, said central raised part hollowed out from the under side of said body part, a flange - opening made in said downwardly-projecting lower end flange, a notch or opening made in said downwardly-projecting side flange adapted to receive the upwardly-projecting marginal flange on the upper end of a similar shingle-tile when the latter is laid beneath the first-mentioned tile in forming a roof, and suitable means for securing said shingle-tile to a roof foundation, 85 all when made substantially as and for the purposes set forth. 90

14. An improved shingle-tile, having an oblong body part with the sides of its lower portion made parallel to each other, the upper portion of said body part made of diminished width to reduce the weight thereof and dispense with unnecessary material therein, upwardly-projecting flanges made on the face of said body part and extended along its sides 100 to the upper end thereof, a downwardly-projecting flange made on the under side of said body part and extended along the sides and end of the lower portion thereof, said upwardly-projecting flanges suitably notched or cut away to receive the aforesaid downwardly-projecting lower end flange of a similar tile when the latter is laid above the first-mentioned tile in forming a roof, and suitable means for securing said shingle-tile to a roof 105 foundation, all when made substantially as and for the purposes set forth. 110

15. An improved shingle-tile, having an oblong body part with the sides of its lower portion made parallel to each other, the upper portion of said body part made of diminished width to reduce the weight thereof and dispense with unnecessary material therein, upwardly-projecting flanges made on the face of said body part and extended along its sides to the upper end thereof, a downwardly-projecting flange made on the under side of said body part and extended along the sides and end of the lower portion thereof, with a flange-opening made in said downwardly - projecting 125 130

flange on the lower end of said body part, and suitable means for securing said shingle-tile to a roof foundation, all when made substantially as and for the purposes set forth.

16. An improved shingle-tile, having a body part made of an oblong outline, upwardly-projecting flanges made on the face portion of said body part and extended along the sides to the upper end of said body part, a downwardly-projecting flange made on the under side of said body part along its sides and lower end, a central raised part made on the lower portion of the face of said body part, said central raised part hollowed out from the under side of said body part and made with a transverse closing part set back under, so as to form a recess or hood at the lower end of said central raised part, a flange-opening made in the aforesaid transverse closing part, a downwardly-projecting transverse joint-closing rib α made on the under side of said body part, as shown, and suitable means for securing said shingle-tile to a roof foundation, all when made substantially as and for the purposes set forth.

17. An improved shingle-tile, having a body part made of an oblong outline, upwardly-projecting flanges made on the face portion of said body part and extended along the sides to the upper end of said body part, a downwardly-projecting flange made on the under side of said body part along its sides and lower end, a central raised part made on the lower portion of the face of said body part, said central raised part hollowed out from the under side of said body part and made with a transverse closing part set back under, so as to form a recess or hood at the lower end of said central raised part, a flange-opening made in the aforesaid transverse closing part, an upwardly-projecting joint-closing part v made on the top of an upwardly-projecting side flange made on the face of said body part, as shown, and suitable means for securing said shingle-tile to a roof foundation, all when made substantially as and for the purposes set forth.

18. An improved shingle-tile, having an oblong body part with the sides of its lower portion made parallel to each other, the upper portion of said body part made of diminished width to reduce the weight thereof and dispense with unnecessary material therein, upwardly-projecting flanges made on the face of said body part and extended along its sides to the upper end thereof, a downwardly-projecting flange made on the under side of said body part along the sides and end of the lower portion thereof, a central raised part made on the lower portion of the face of said body part, said central raised part hollowed out from the under side of said body part and made with a transverse closing part set back under, so as to form a recess or hood at the lower end of said central raised part, a flange-opening made

in said transverse closing part, an upwardly-projecting joint-closing part v' made on the top of an upwardly-projecting side flange on the face side of said body part, as shown, and suitable means for securing said shingle-tile to a roof foundation, all when made substantially as and for the purposes set forth.

19. An improved shingle-tile, having a body part made of an oblong outline, an upwardly-projecting flange made on the face portion of said body part and extended along one side up to and across the upper end and down along the other side of said body part, a downwardly-projecting flange made on the under side and lower end of said body part, a flange-opening made in said lower-end flange, a notch or opening made in said downwardly-projecting flange adapted to receive the upwardly-projecting marginal flange on the upper end of a similar tile when the latter is laid beneath the first-mentioned tile in forming a roof, a central raised part made on the face of the lower portion of said body part, said central raised part hollowed out from the under side of said body part, a downwardly-projecting transverse joint-closing rib α made on the under side of said body part, as shown, and suitable means for securing said shingle-tile to a roof foundation, all when made substantially as and for the purposes set forth.

20. An improved shingle-tile, having a body part made of an oblong outline, an upwardly-projecting flange made on the face portion of said body part and extended along one side up to and across the upper end and down along the other side of said body part, a downwardly-projecting flange made on the under side and lower end of said body part, a flange-opening made in said downwardly-projecting lower end flange, a notch or opening made in said downwardly-projecting side flange adapted to receive the upwardly-projecting marginal flange on the upper end of a similar shingle-tile when the latter is laid beneath the first-mentioned shingle-tile in forming a roof, a central raised part made on the face of the lower portion of said body part, said central raised part hollowed out from the under side of said body part, an upwardly-projecting transverse joint-closing rib w made on the face of said body part, and suitable means for securing said shingle-tile to a roof foundation, all when made substantially as and for the purposes set forth.

21. An improved shingle-tile, having a body part made of an oblong outline, an upwardly-projecting flange made on the face portion of said body part and extended along one side up to and across the upper end and down along the other side of said body part, a downwardly-projecting flange made on the under side and lower end of said body part, a central raised part made on the face of the lower portion of said body part, said central raised part hollowed out from the under side

- of said body part, a flange-opening made in said downwardly-projecting lower end flange, an upwardly-projecting joint-closing part v made on the top of an upwardly-projecting 5 side flange made on the face of said body part, as shown, a notch or opening made in said downwardly-projecting side flange adapted to receive the upwardly-projecting marginal flange on the upper end of a similar shingle-
tile when the latter is laid beneath the first-mentioned tile in forming a roof, and suitable means for securing the tile to a roof foundation, all when made substantially as and for the purposes set forth.
- 15 22. An improved shingle-tile, having a body part made of an oblong outline, an upwardly-projecting flange made on the face portion of said body part and extended along one side and the upper end of said body part, a downwardly-projecting flange made on the under side of said body part at its lower end, a downwardly-projecting longitudinally-disposed rib or flange also made on the under side of said body part, a notch or opening 20 made in said latter flange or rib adapted to receive the upwardly-projecting marginal flange on the upper end of a similar shingle-tile when the latter is laid beneath the first-mentioned shingle-tile in forming a roof, a central raised part made on the lower portion 30 of the face of said body part, said central raised part hollowed out from the under side of the body part and made with a transverse closing part set back under, so as to form a recess or hood, a flange-opening made in said 35 transverse closing part, a guard-rib made across the upper part of the hollowed-out portion of said central raised part, an upwardly-projecting joint-closing part v made on the top of an upwardly-projecting side flange 40 made on the face of said body part, as shown, and suitable means for securing said shingle-tile to a roof foundation, all when made substantially as and for the purposes set forth.
- In testimony whereof I have signed my name 45 to this specification in the presence of two subscribing witnesses.

LESLIE G. SHARP.
